UNITED STATES PATENT OFFICE

HARRY M. SWINDLER, OF DAYTON, OHIO, ASSIGNOR TO THE JAMES LEFFEL & COMPANY, OF SPRINGFIELD, OHIO, A CORPORATION OF OHIO

INTERMITTENT DRIVING MECHANISM

Application filed February 1, 1930. Serial No. 425,208.

My invention relates to intermittent driving mechanism.

It is a particular object of my invention to provide an intermittent driving mechanism for stokers, although it is adaptable to other purposes.

It is the object of my invention to provide a driving mechanism, one part of which is continuously operated and the other part of 10 which is intermittently operated.

It is a further object to provide for such intermittent operation at predetermined intervals, which will automatically re-occur without further setting of the mechanism.

15 It is my object to provide means of adjusting the mechanism to operate at predetermined intervals.

It is a further object to provide means of rendering the mechanism inoperative if there 20 is any obstruction to the means that is being operated.

It is a further object to provide means to cause the stoker to operate intermittently at predetermined intervals for a predetermined 25 number of revolutions, or continuously or hold it at rest.

Referring to the drawings:

Figure 1 is a top plan view;

Figure 2 is a rear elevation from the operating side where the adjustment of the 30 mechanism is accomplished;

Figure 3 is a section on the line 3—3 of Figure 1;

Figure 4 is a section on the line 4—4 of 35 Figure 1;

Figure 5 shows one end of a stoker retort and pusher in position to be operated by the operating mechanism, with the motor and blower in position;

40 Figure 6 is a diagrammatic view partly in section showing the several parts in position where the driven shaft is at rest;

Figure 7 is a similar view showing the driven shaft in operation;

45 Figure 8 is a similar view showing the driven shaft in operation with the parts in preparatory position to render it inoperative;

50 Figure 9 is a detail view, partly in section,

of the adjusting mechanism shaft and its associated ratchets and pawls;

Referring to the drawings in detail, 1 is a housing containing lubricant, which has bolted to its rear wall 2 a supplementary 55 housing for the adjustment and safety mechanism, designated 3. It is attached by the bolts 4 to the housing 1. A suitable cover 5 is mounted on the main housing.

The lower end of the main housing 1 is 60 provided with the tapered roller bearing 6 for receiving the driven shaft 7. This shaft is retained in position at its upper end by the roller bearing 8, which is carried by the cover plate 5. On the driven shaft is mounted a 65 suitable crank 9 for attachment to the stoker arm or equivalent mechanism, which is to be driven in conjunction with the driven shaft 7.

The shaft 10, which is supported horizontally in the casing 1, carries a worm 11 that 70 engages with a worm gear 12. This worm gear is bolted by the bolts 13 on to a plate 14 of a sleeve 16 that turns freely upon the driven shaft 7. The sleeve 16 carries an elongated gear 17. The sleeve is supported on 75 the roller bearings 18, the outer face of which rests upon the shoulder 19 of the planetary gear carrier 20. The shaft 10, motor 10^a, worm 11, gear 12, sleeve 16 and its gear 17 turn continuously. The planetary gear carrier 20 operates intermittently.

Planetary gear carrier

The planetary gear carrier is provided with 80 a plurality of vertically-disposed shafts 21, which carry planetary gear pinions 22 that mesh with the gear 17. These gears also mesh with a ring or orbit gear 23 which is carried on a ring gear carrier 24. The ring gear carrier rests upon the ends of the gears 22. This completes the planetary gear mechanism.

The ring gear carrier 24 is provided with 85 an eccentric cam 25 which operates the setting mechanism for determining the period of the cycle of operations of the mechanism.

The ring gear carrier also carries the ring gear carrier disc 26, which engages with a ring gear carrier release arm, the opera- 100

tion of which, when in engaging position, is to hold stationary the ring gear carrier.

Planetary gear carrier operating mechanism

5 The planetary gear carrier has a cam 27, known as a re-set cam, which serves to reset the mechanism, hereinafter described, that eventually stops the planetary gear carrier. The planetary gear carrier also carries a disc 28 which is utilized to stop in conjunction with the holding arm the planetary gear carrier and thereby bring to rest the driven shaft 7 to which the planetary gear carrier is attached by the key 29.

10 This disc 28 is provided with a depression 30 which receives the roller 31 on the planetary gear carrier holding arm 32. This arm 32 is provided with a laterally extending shoulder 33 for receiving a returning spring 34, the other end of which at 35 is mounted on the inside of the casing 1. The arm 32 carries an upwardly projecting lug 36, the function of which will be hereinafter explained. The arm 32 is mounted by a key 25 37 on shaft 38 known as the re-set shaft.

Re-set mechanism

This re-set shaft carries on it loosely a sleeve 39 which supports a laterally-extending re-set arm 40 carrying a roller 41 that is engaged by the arcuate cam face 42 of the re-set cam 27. It rolls upon the face 43 for a period before dropping off and descending along the face 44. The arm 40 is provided with a depending lug 45 that engages the lug 36 on the arm 32. The sleeve 39 also carries a projecting arm 46 which is pivotally attached at 47 to one end of a trip plunger 48. This trip plunger carries on one end the spring 49, the other end of which at 50 is mounted within the casing 1. This is known as the trip plunger load spring. The other end of this arm and its associated mechanism will be explained in connection with the setting mechanism for determining the number of revolutions per cycle of operation for the driven mechanism.

Ring gear operating mechanism

50 The following mechanism is provided for stopping or releasing the movement of the ring gear.

A sleeve 51 mounted on the shaft 38 turns loosely thereon. This sleeve is extended upwardly, forming a sleeve of restricted diameter as at 52 which extends through the bearing 53 in the cover 54 of the casing. Upon the sleeve 52 is mounted the safety reset handle 55. The upper end of the sleeve 52 is provided with a V-shaped safety notch 56. This notch receives a V-shaped projection 57 on the safety release sleeve 58 which has a square opening 59 mounted on the square end of the shaft 38 at 60. The safety release sleeve 58 is spring pressed into lock-

ing engagement by the spring 61, the tension of which is adjusted by the threaded nut 62 mounted on the shaft 38. Upon any resistance to the further operation of the driven mechanism, the safety release sleeve 58 is driven upwardly thereby releasing the driving mechanism and preventing disastrous rupture of the parts.

70 The sleeve 51 carries the arm 63, which has on its end the roller 64 that rides upon the peripheral surface 65 of the disc 26, along the cam surface 66 of a notch and against the stopping surface 67. When this release arm 63 is in its inner position, it stops the movement of the ring gear carrier. The angle of the face 67 is 15° to the arc of movement of roller 64 facilitating its kick out when pressure is applied; the movement of arm 63 is along the line of the resultant of these forces.

Cycle of operation setting mechanism

75 The principle of operation of this mechanism is to have the rotation of the driving mechanism i. e. ring gear carrier, with its cam 25 operate a step-by-step mechanism to bring a releasing disc 70 described later known as a trip cam into position to release the trip plunger 48 thereby permitting the mechanism to function so that the ring gear carrier may be held in a stationary position 95 while the continuously operating mechanism, such as the shaft 10, motor 10^a, gears 11, 12, 17 and 22 will continue to operate to rotate the planetary ring gear carrier which is free to move as its release arm 32 is then in inoperative position.

100 This will continue until the parts are adjusted for another cycle of operations and another period of movement of the driven shaft 7, as will be hereinafter described.

105 This cycle adjusting mechanism comprises the following. A vertically-disposed shaft 68 is supported within the sleeve 69 at the bottom of the casing. Integrally formed on this shaft 68 is a trip disc 70 which is provided with a cutaway face 71 and a shoulder 72 communicating therewith and with the periphery of the disc. This shaft 68 is furthermore provided with a ratchet 73 formed on a sleeve 73^b splined thereto or integral therewith to rotate it. The ratchet 73 has a blank portion 73^a for use when the index handle 97 is in "off" position. The ratchet is rotated by the step-by-step pawl 74 which is pivoted at 75 in a carrier 76 mounted for oscillation about the sleeve 73^b. This pawl is provided with a laterally projecting shoulder 77 which extends between ears 78 of the arm 79 which carries a roller 80 engaging the periphery of the cam 25. This arm is known as a timer feed arm. The arm is mounted for oscillation upon the sleeve 81.

115 The pawl 74 is broad enough to span the ratchet 73 and the ratchet 82 mounted to rotate independent of the ratchet 73. This 120

ratchet 82 is provided with a fewer number of teeth, the exact number of which, as compared with the teeth of the ratchet 73, will determine the period of continuous operation of the shaft 7 and associated mechanism, or, in other words, the number of strokes per minute of the crank 9 which may be desired while the mechanism is operating. The walls of the teeth of ratchet 82 are the same slope as the teeth of the ratchet 73 so that the outer edge of each tooth of ratchet 82 has a cam surface. The walls of the teeth of the ratchet 82 are in line with the walls of certain of the teeth of the ratchet 73. This is due to the fact that the space between the teeth of the ratchet 82 will determine how long an interval must elapse before the tooth of the pawl 74 can drop into the ratchet 73 to actuate it one tooth and, therefore, how many revolutions it will take of the ring gear carrier 24 and cam 25 to move this arm 79 with the pawl 74 up into position to engage the tooth of the ratchet 73.

The arm 79 is constantly fed up for this purpose upon each actuation of it by the cam 25 in order to actuate the ratchet 83 which is connected to and rotates the ratchet 82 so as to move that ratchet to a position where the pawl tooth 74 can drop into the ratchet 73. Movement is imparted to the ratchet 83 by the pawl 84 which is carried on the shaft 75 in the carrier 76 and moves with the arm 79.

Thus, the step-by-step movement of the arm 79 through the continued rotation of the eccentric cam 25 moves the disc 82 which is holding out the pawl 74 from the ratchet 73 step-by-step. The spring 85 serves to keep the arm 79 and its roller 80 into engaging position with the cam 25.

While this is occurring, the result of moving the ratchet 73 is to rotate the shaft 68 and its disc 70 which will eventually permit the trip arm 48 to drop off the shoulder 72 of that disc which results, as will be herein-after explained, in moving through the impetus of the spring 49 the planetary gear carrier arm 32 into inoperative position and the holding arm of the ring gear carrier into operative position to hold that gear to cause the shaft 7 and crank 9 to be driven. This results from the movement of the disc 70 in winding the timing spring 95.

Extending from the housing 1 is a bracket 88 which has two arms through the outer ends of which the shaft 87 extends. On this shaft is a sleeve 90 adapted to rotate on the shaft or to rotate with the shaft in the arms of the bracket 88. Extending from the sleeve 90 and integral therewith is a link 89 pivoted at its outer end at the point 91 to the trip arm 48. Located above the sleeve 90 and between the sleeve and one of the arms is a pawl 94, adapted to engage one of the ratchet wheels 83 and hold it against backward rotation.

There is also located on this shaft 87 a second pawl 86 between the pawl 94 and the sleeve 90. This pawl engages the teeth of the ratchet wheel 73 to prevent backward rotation thereof. The pawl 86 has a shoulder 93 adapted to be engaged by a shoulder 92 on the sleeve. The shoulder 92 engages the shoulder 93 to trip the pawl 86 when the trip arm is drawn backward to engage the outer periphery of the disc 70 so that the spring 95 may reposition the shaft 68 for further operation of the shaft 7 and through it the stoker mechanism.

The pawl 94 is pivoted on the shaft 87 and engages the ratchet 83 to hold it against backward movement. Resisting the movement imparted to the ratchet 73 by the pawl 74 through the agency of the arm 79 is a spring 95, one end of which is connected to the sleeve carrying the ratchet 73 and the other end of which is connected to the rotatably-mounted sleeve 96 having the handle 97 which is positioned by locating the shoulder 98 in one of the slots 99 in the cover 100. The purpose of this spring is to automatically return the ratchet 73, and cam 70, to a position corresponding to that of the index lever setting on top of gear box which has a definite relation to the "trip" position, or position where the trip plunger 48 will drop off the cam shoulder 72, when the reset mechanism lifts the holding pawl 86. When the ring gear carrier 24 comes to rest, eccentric cam 25 has passed its farthest out position and spring 85 is moving the arm 79 toward the center of the shaft 7, and the ear 78 of arm 79 is holding the pawl 74 out of engagement with the ratchet 73 and when the holding pawl 86 is lifted by the shoulder 92 engaging the shoulder 93, tension of timing spring 95 returns the cam 70 to a position corresponding to setting of the index on top of the gear box.

Method of operation

When the parts are shown, as in Figure 6, the planetary gear carrier is stationary because the arm 32 has its roller 31 in the disc depression 30 and the carrier 20 is prevented from rotative movement. The shaft 7 and the crank 9 are stationary.

The gears 22 being in mesh with the rotating ring gear 23 carried by the ring gear carrier 24 are rotating, since, the gear 17 which is driving those two gears is rotating with its sleeve 16, gear 12, gear 11 and shaft 10 which is driven by a motor. The gear 101 which meshes with the gear 11 has a lubrication gear for picking up lubricant from the pool of lubricant in the casing 1 to deliver it to its associated gears.

The pressure of the spring 49 maintains the end of the trip plunger 48 on the periphery of the disc 70. The constantly rotating eccentric cam 25 is moving the lever 79 each time it rotates, thereby moving the ratch-

et 73 towards the position where the pawl 74 can drop into a tooth thereof to actuate the ratchet 73 and its associated disc 70.

When such a movement has taken place 5 and the disc 70 is rotated to a point where the end of the trip plunger 48 can drop off the shoulder 72 on to the surface 71 of the disc 70, the spring 49 then transfers its energy to a movement of the lever 63 inwardly to enable 10 gaging position with the ring gear carrier so that it will eventually engage the surface 67 of the cam 65 and stop the ring gear carrier from further movement.

The movement of the trip plunger 48 as it 15 is connected at 47 to the ear 46 of the lever 40, which is loosely mounted on the shaft 38, moves that lever so that its lug 45 engages the lug 36 to actuate the lever 32 to move this roller 31 out of the depression 30 and thereby 20 unlock the planetary gear carrier 20.

The parts are now moved into position shown in Figure 7. As the ring gear carrier is stationary, the planetary gear will transmit movement to the shaft 7.

25 This continues until the re-set cam 27 which is traveling with the planetary gear carrier that is now rotating about the axis of the shaft 7 with it until the surface 42 engages the roller 41 moving the lever 40 to its 30 outermost position where it is maintained while it rides upon the surface 43. This permits the lever 32 to have its roller 31 rest upon the periphery of the disc 28 and to freely drop into the cutaway portion 30 under the 35 impulse of the spring 34 when that disc comes opposite the roller 31. This is made possible by the removal of the shoulder 45 of the lever 40 from engagement with the shoulder 36 of the lever 32 by the movement of the lever 40 to its outermost position. This further results in a backward movement of the trip 40 plunger 48 which detaches the holding pawl 86 to permit the re-set spring 95 to re-set the disc 70 in a new position so as to receive and 45 maintain the trip plunger 48 in the position shown in Figure 6 when it is permitted to return to engage the disc 70. This is accomplished when the roller 41 drops off of the cam face 43 along the face 44.

50 As the arms 32 and 63 move together normally, the entry of one into its cam groove moves the other out of position. In the event the driven mechanism is resisted in its operation, the connection between these two arms 55 through the safety lock 59 and spring 61 permits of their disconnection by the safety angle of 67 which it makes with the arm 63 to throw said arm outwardly and a consequent rupture of the mechanism.

50 The movement of the handle connected to this safety lock, which handle is designated 55, will indicate to the operator by the movement of that handle to the "out" position that something is interfering with the free operation of the mechanism.

An oil gauge consisting of a gauge rod 103 is provided for indicating the height of lubricant in the casing. An orifice is closed by the plug 104.

In "off" position of the index handle 97 the pawl 74 rests on the blank part 73a of the ratchet 73, and the timer will not feed up so that the shaft 7 remains stationary as long as the index lever 97 remains in "off" position.

When the index handle 97 is in the position indicated by the word "Bank" the tension of the spring 95 is released and the position of the shaft 68 is such that the pawl for operating this shaft cannot engage the teeth of the ratchet wheel 73 for rotating the disc 70. In this position the shaft 7 rotates continuously. When the index handle 97 is in the position shown in Figure 1 the shaft 68 and the disc 70 are so positioned with relation to the trip arm 48 and the other parts of the mechanism that the stoker shaft 7 is not operated.

When the index handle 97 is positioned between these two extremes, with the lug 98 engaging with any of the notches 99, the stoker operating shaft 7 has intermittent movements, the period of time between the movements depending upon the position of the index handle 97. As the index handle 97 approaches the word "Off" and the point on the end of the index handle approaches the word "Bank," the period of time between the successive rotation of the shaft 7 is gradually diminished until the index point reaches the word "Bank," at which time the stoker shaft continuously rotates. As the index handle approaches the word "Bank" the time between the periods of rotation of the shaft 7 increases gradually until the handle reaches the point shown in Figure 1, at which time the stoker shaft 7 does not rotate at all.

It will be understood that I desire to comprehend within my invention such modifications as may be necessary to adapt it to varying conditions and uses.

Having thus fully described my invention, what I claim as new and desire to secure by Letters Patent, is:

1. In combination, a driven means, a driving means, planetary gearing therebetween, means to render a portion of said planetary gearing stationary to establish a connection between the driven means and the driving means, and means including a pawl and ratchet operated by a portion of the planetary gearing to time the period of holding said means stationary.

2. In combination, a driven means, a driving means, planetary gearing therebetween, means to render a portion of said planetary gearing stationary to establish a connection between the driven means and the driving means, means to time the period of holding said means stationary, and means on the

driven means to determine said timing period.

3. In combination, a driven means, a continuously operated driving means, intermediate means for connecting the driving and the driven means comprising alternately moving means so arranged that when one alternately moving means is moving with the continuously operating means the driven means and the other alternately moving means will be stationary and when the alternately moving means that was driven by the continuously driven means is stationary the other alternately moving means and the driven means will be moving, and means operated by one of said means for timing the holding of the respective means.

4. In combination, a driving shaft, a driven shaft, a ring gear carrier, a driving gear driven by said driving shaft continuously, a planetary gear carrier having gears engaging said continuously operating gear and the ring gear, holding cams on said ring gear carrier and the planetary gear carrier, and ring gear carrier operated means for alternately holding said ring gear carrier and planetary gear carrier through the agency of said cams.

5. In combination, a driving shaft, a driven shaft, a ring gear carrier, a driving gear driven by said driving shaft continuously, a planetary gear carrier having gears engaging said continuously operating gear and the ring gear, holding cams on said ring gear carrier and the planetary gear carrier, ring gear carrier operated means for alternately holding said ring gear carrier and planetary gear carrier through the agency of said cams, and means including a pawl and ratchet operated by one of said carriers for determining the period of its being held and released.

6. In combination, a driving shaft, a continuously operating gear driven thereby, a driven shaft, a ring gear carrier having a ring gear, a planetary gear carrier having planetary pinions engaging said gears, said last named carrier being connected to said driven shaft, and ring gear carrier operated automatic means for alternately holding said ring gear carrier and planetary gear carrier whereby said driven shaft is intermittently driven.

7. In combination, a driving shaft, a continuously operating gear driven thereby, a driven shaft, a ring gear carrier having a ring gear, a planetary gear having planetary pinions engaging said gears, said carrier being connected to said driven shaft, means for alternately holding said ring gear carrier and planetary gear carrier whereby said driven shaft is intermittently driven, said holding means being interconnected.

8. In combination, a driving shaft, a continuously operating gear driven thereby, a driven shaft, a ring gear carrier having a ring gear, a planetary gear having planetary

pinions engaging said gears, said carrier being connected to said driven shaft, means for alternately holding said ring gear carrier and planetary gear carrier whereby said driven shaft is intermittently driven, said holding means being interconnected, and a safety means interposed between said holding means whereby an obstruction to the operation of said driven means will result in rendering said holding means connection inoperative.

9. In combination, a driving means, a gear driven thereby, a ring gear carrier, a planetary gear carrier having gears engaging the preceding gears, a driven shaft connected to said planetary gear carrier, holding means for alternately holding said ring gear and planetary gear carriers, and pawl and ratchet operated timing means operated by one of said carriers for timing the alternate holding and release of said carriers.

10. In combination, a driving means, a gear driven thereby, a ring gear carrier, a planetary gear carrier having gears engaging the preceding gears, a driven shaft connected to said planetary gear carrier, holding means for alternately holding said ring gear and planetary gear carriers, pawl and ratchet operated timing means operated by one of said carriers for timing the alternate holding and release of said carriers, said holding means for the respective carriers being interconnected in order to operate alternately.

11. In combination, a driving means, a gear driven thereby, a ring gear carrier, a planetary gear carrier having gears engaging the preceding gears, a driven shaft connected to said planetary gear carrier holding means for alternately holding said ring gear and planetary gear carriers, timing means operated by one of said carriers for timing the alternate holding and release of said carriers, said holding means for the respective carriers being interconnected in order to operate alternately, said timing means being operated by the ring gear carrier.

12. In combination, a driving means, a gear driven thereby, a ring gear carrier, a planetary gear carrier having gears engaging the preceding gears, a driven shaft connected to said planetary gear carrier holding means for alternately holding said ring gear and planetary gear carriers, timing means operated by one of said carriers for timing the alternate holding and release of said carriers, said holding means for the respective carriers being interconnected in order to operate alternately, said timing means being operated by the ring gear carrier, and a safety connection between said holding means whereby a predetermined resistance to the operation of the mechanism will permit a relative movement between said respective holding means.

13. In combination, a driving means, gearing driven thereby, a ring gear carrier and ring gear, a planetary gear carrier and gears engaging said preceding gears, a driven shaft connected to said planetary gear carrier means for alternately stopping said respective carriers, including a kick-out cam on the planetary gear carrier, interconnected holding means for holding said respective carriers alternately, and a kick-out means associated therewith actuated by said kick-out cam for intermittently actuating said holding means.

14. In combination, a driving means, gearing driven thereby, a ring gear carrier and ring gear, a planetary gear carrier and gears engaging said preceding gears, a driven shaft connected to said planetary gear carrier means for alternately stopping said respective carriers, including a kick-out cam on the planetary gear carrier, interconnected holding means for holding said respective carriers alternately, a kick-out means associated therewith actuated by said kick-out cam for intermittently actuating said holding means, a timing cam on said ring gear carrier, and timing means actuated thereby, whereby the period of holding the respective carriers will be determined.

15. In combination, a driving means, gearing driven thereby, a ring gear carrier and ring gear, a planetary gear carrier and gears engaging said preceding gears, a driven shaft connected to said planetary gear carrier means for alternately stopping said respective carriers, including a kick-out cam on the planetary gear carrier, interconnected holding means for holding said respective carriers alternately, a kick-off means associated therewith actuated by said kick-out cam for intermittently actuating said holding means, a timing cam on the ring gear carrier, a timing means actuated thereby, a trip plunger controlled by the timing means and connected to the kick-out means whereby at a predetermined movement of said timing cam, said stopping means for the respective carriers will be moved inwardly and outwardly.

16. In combination, a driving means, gearing driven thereby, a ring gear carrier and ring gear, a planetary gear carrier and gears engaging said preceding gears, a driven shaft connected to said planetary gear carrier means for alternately stopping said respective carriers, including a kick-out cam on the planetary gear carrier, interconnected holding means for holding said respective carriers alternately, a kick-out means associated therewith actuated by said kick-out cam for intermittently actuating said holding means, a timing cam on said ring gear carrier, timing means actuated thereby, whereby the period of holding the respective carriers will be determined, and a safety

means between said stopping means to render them relatively inoperative and to render said driven shaft inoperative in the event of a predetermined resistance to the movement thereof.

17. In combination, a driving shaft, gearing driven thereby, a ring gear and carrier, a planetary gear and carrier and gears meshing with said gears, a driven shaft connected to said planetary gear carrier, a timing cam on the ring gear carrier, holding cams on said respective carriers, interconnected holding arms for alternately holding said carriers through the cams, a timing arm engaging the timing cam, timing means actuated by the timing arm and means interconnecting said holding arms and the timing means actuated by the timing arm and timing cam for timing the alternate periods of holding and releasing of said carriers.

18. In combination, a driving shaft, gearing driven thereby, a ring gear and carrier, a planetary gear carrier and gears meshing with said gears, a driven shaft connected to said planetary gear carrier, a timing cam on the ring gear carrier, holding cams on said respective carriers, interconnected holding arms for alternately holding said carriers through the cams, a timing arm engaging the timing cam, means interconnecting said holding arms and the timing means actuated by the timing arm and timing cam for timing the alternate periods of holding and releasing of said carriers, a kick-out cam carried by said planetary gear carrier, a kick-out arm adapted to actuate said holding arms and interconnected to the means timing the movement of said arms.

19. In combination, a driving shaft, gearing driven thereby, a ring gear and carrier, a planetary gear carrier and gears meshing with said gears, a driven shaft connected to said planetary gear carrier, a timing cam on the ring gear carrier, holding cams on said respective carriers, interconnected holding arms for alternately holding said carriers through the cams, a timing arm engaging the timing cam, means interconnecting said holding arms and the timing means actuated by the timing arm and timing cam for timing the alternate periods of holding and releasing of said carriers, a kick-out cam carried by said planetary gear carrier, a kick-out arm adapted to actuate said holding arms and interconnected to the means timing the movement of said arms, and means to adjust said timing means to determine the number of revolution between the stopping and starting of the respective carriers.

20. In combination, a driving means, a driven means, planetary gearing means therebetween, means for alternately holding the parts of the planetary gearing means for alternately driving the driven means, timing

means including a pawl and ratchet associated therewith operating when the driven means operates for controlling the number of revolutions of said driven means and the alternate holding of the respective parts of the planetary gearing.

21. In combination, a ring gear carrier normally rotating, a planetary gear carrier normally stationary, a driven shaft connected thereto, gears on said respective carriers, and means for continuously operating said gears, holding cams on the respective carriers, interconnected holding arms alternately engaging said cams, a kick-out cam on the planetary gear carrier, a kick-out arm operated thereby adapted to engage and move outwardly the holding arm for said carrier, a trip plunger connected to said kick-out arm, yielding means connected thereto, a cam supporting said trip plunger and resisting said yielding means, timing means for moving said cam to release said trip plunger, and a timing cam on said ring gear carrier actuating said timing means whereby upon the release of the trip plunger by its cam, the trip plunger yielding means will actuate the kick-out arm and through it said holding arms, and step-by-step mechanism associated with said trip plunger cam and the timing cam, and means for adjusting the movement of said step-by-step means per revolution of the driven means whereby the period of operation of the driven means is controlled, and means for holding said step-by-step and trip plunger cam means against return movement, said means being released by the actuation of the kick-out arm through the kick-out cam.

22. In combination, a ring gear carrier normally rotating, a planetary gear carrier normally stationary, a driven shaft connected thereto, gears on said respective carriers, and means for continuously operating said gears, holding cams on the respective carriers, interconnected holding arms alternately engaging said cams, a kick-out cam on the planetary gear carrier, a kick-out arm operated thereby adapted to engage and move outwardly the holding arm for said carrier, a trip plunger connected to said kick-out arm, yielding means connected thereto, a cam supporting said trip plunger and resisting said yielding means, timing means for moving said cam to release said trip plunger, and a timing cam on said ring gear carrier actuating said timing means whereby upon the release of the trip plunger by its cam, the trip plunger yielding means will actuate the kick-out arm and through it said holding arms.

23. In combination, a ring gear carrier normally rotating, a planetary gear carrier normally stationary, a driven shaft connected thereto, gears on said respective carriers, and means for continuously operating said gears, holding cams on the respective carriers, interconnected holding arms alternately engaging said cams, a kick-out cam on the planetary gear carrier, a kick-out arm operated thereby adapted to engage and move outwardly the holding arm for said carrier, a trip plunger connected to said kick-out arm, yielding means connected thereto, a cam supporting said trip plunger and resisting said yielding means, timing means for moving said cam to release said trip plunger, and a timing cam on said ring gear carrier actuating said timing means whereby upon the release of the trip plunger by its cam, the trip plunger yielding means will actuate the kick-out arm and through it said holding arms, and step-by-step mechanism associated with said trip plunger cam and the timing cam, and means for adjusting the movement of said step-by-step means per revolution of the driven means whereby the period of operation of the driven means is controlled.

24. In combination, a ring gear carrier normally rotating, a planetary gear carrier normally stationary, a driven shaft connected thereto, gears on said respective carriers, and means for continuously operating said gears, holding cams on the respective carriers, interconnected holding arms alternately engaging said cams, a kick-out cam on the planetary gear carrier, a kick-out arm operated thereby adapted to engage and move outwardly the holding arm for said carrier, a trip plunger connected to said kick-out arm, yielding means connected thereto, a cam supporting said trip plunger and resisting said yielding means, timing means for moving said cam to release said trip plunger, and a timing cam on said ring gear carrier actuating said timing means whereby upon the release of the trip plunger by its cam, the trip plunger yielding means will actuate the kick-out arm and through it said holding arms, and step-by-step mechanism associated with said trip plunger cam and the timing cam, and means for adjusting the movement of said step-by-step means per revolution of the driven means whereby the period of operation of the driven means is controlled.

wardly the holding arm for said carrier, a trip plunger connected to said kick-out arm, yielding means connected thereto, a cam supporting said trip plunger and resisting said yielding means, timing means for moving said cam to release said trip plunger, and a timing cam on said ring gear carrier actuating said timing means whereby upon the release of the trip plunger by its cam, the trip plunger yielding means will actuate the kick-out arm and through it said holding arms, and step-by-step mechanism associated with said trip plunger cam and the timing cam, and means for adjusting the movement of said step-by-step means per revolution of the driven means whereby the period of operation of the driven means is controlled, and means for holding said step-by-step and trip plunger cam means against return movement, said means being released by the actuation of the kick-out arm through the kick-out cam.

25. In combination, driving means, a driven means, planetary gearing means therebetween, a pair of interconnected, alternately engaging arms for holding the respective parts of the planetary gearing, holding cams on said respective parts engaged by the arms, a kick-out cam, a kick-out arm adapted to actuate said first mentioned arms in one direction, a trip plunger connected to said kick-out arm, yielding means actuating the trip plunger, a trip plunger cam engaged by the plunger, step-by-step mechanism to actuate said cam, means connected with the driven means for actuating said step-by-step mechanism whereby the release of the trip plunger by its cam will transfer the action of its yielding means from it to the kick-out arm and from the kick-out arm to the holding arms to change the position thereof and thereafter the opposite movement by the kick-out arm of the kick-out cam will re-set said trip plunger and its cam.

26. In combination, driving means, a driven means, planetary gearing means therebetween, a pair of interconnected, alternately engaging arms for holding the respective parts of the planetary gearing, holding cams on said respective parts engaged by the arms, a kick-out cam, a kick-out arm adapted to actuate said first mentioned arms in one direction, a trip plunger connected to said kick-out arm, yielding means actuating the trip plunger, a trip plunger cam engaged by the plunger, step-by-step mechanism to actuate said cam, means connected with the driven means for actuating said step-by-step mechanism whereby the release of the trip plunger by its cam will transfer the action of its yielding means from it to the kick-out arm and from the kick-out arm to the holding arms to change the position thereof and thereafter the opposite movement by the kick-out arm of the kick-out cam will re-set said trip plunger and its cam, means connecting said hold-

ing arms releasable upon a predetermined resistance to the driven means.

26. In combination, a driving means, a driven means, planetary gearing means therebetween, a pair of interconnected, alternately engaging arms for holding the respective parts of the planetary gearing, holding cams on said respective parts engaged by the arms, a kick-out cam, a kick-out arm adapted to actuate said first mentioned arms in one direction, a trip plunger connected to said kick-out arm, yielding means actuating the trip plunger, a trip plunger cam engaged by the plunger, step-by-step mechanism to actuate said cam, means connected with the driven means for actuating said step-by-step mechanism whereby the release of the trip plunger by its cam will transfer the action of its yielding means from it to the kick-out arm and from the kick-out arm to the holding arms to change the position thereof and thereafter the opposite movement by the kick-out arm of the kick-out cam will re-set said trip plunger and its cam, means connecting said holding arms releasable upon a predetermined resistance to the driven means, and independent yielding means for maintaining the holding arm for the driven means in holding position.

27. In combination in a planetary gear control, interconnected alternately operating holding arms, a kick-out arm moving said arms in one direction, a trip plunger connected to the kick-out arm, yielding means actuating said plunger in one direction and said kick-out arm with the associated arms when the trip plunger is released, a trip plunger cam, step-by-step mechanism therefor, a holding pawl holding said mechanism against return movement releasable by the outward movement of said trip plunger, and means actuated by said planetary gearing for actuating said step-by-step mechanism.

28. In combination in a planetary gear control, interconnected alternately operating holding arms, a kick-out arm moving said arms in one direction, a trip plunger connected to the kick-out arm, yielding means actuating said plunger in one direction and said kick-out arm with the associated arms when the trip plunger is released, a trip plunger cam, step-by-step mechanism therefor, a holding pawl holding said mechanism against return movement releasable by the outward movement of said trip plunger, and means actuated by said planetary gearing for actuating said step-by-step mechanism, and means timing the movement of said step-by-step mechanism per interval of time and the revolutions of the driven portion of the planetary gearing.

29. In combination in a planetary gear control, interconnected alternately operating holding arms, a kick-out arm moving said arms in one direction, a trip plunger con-

nected to the kick-out arm, yielding means actuating said plunger in one direction and said kick-out arm with the associated arms when the trip plunger is released, a trip plunger cam, step-by-step mechanism therefor, a holding pawl holding said mechanism against return movement releasable by the outward movement of said trip plunger, and means actuated by said planetary gearing for actuating said step-by-step mechanism, means timing the movement of said step-by-step mechanism per interval of time and the revolutions of the driven portion of the planetary gearing, and means for returning to initial position said step-by-step mechanism and trip plunger cam.

30. In combination in a planetary gear control, interconnected alternately operating holding arms, a kick-out arm moving said arms in one direction, a trip plunger connected to the kick-out arm, yielding means actuating said plunger in one direction and said kick-out arm with the associated arms when the trip plunger is released, a trip plunger cam, step-by-step mechanism therefor, a holding pawl holding said mechanism against return movement releasable by the outward movement of said trip plunger, and means actuated by said planetary gearing for actuating said step-by-step mechanism, means timing the movement of said step-by-step mechanism per interval of time and the revolutions of the driven portion of the planetary gearing, means for returning to initial position said step-by-step mechanism and trip plunger cam, a yieldable connection between said holding arms to permit their relative movement upon a predetermined resistance to the driven means.

31. In combination in a planetary gear control, interconnected alternately operating holding arms, a kick-out arm moving said arms in one direction, a trip plunger connected to the kick-out arm, yielding means actuating said plunger in one direction and said kick-out arm with the associated arms when the trip plunger is released, a trip plunger cam, step-by-step mechanism therefor, a holding pawl holding said mechanism against return movement releasable by the outward movement of the trip plunger, and means actuated by said planetary gearing for actuating said step-by-step mechanism, means timing the movement of said step-by-step mechanism per interval of time and the revolutions of the driven portion of the planetary gearing, means for returning to initial position said step-by-step mechanism and trip plunger cam, a yieldable connection between said holding arms to permit their relative movement upon a predetermined resistance to the driven means, an independent yielding means for actuating the holding means for the driven mechanism into holding position.

32. In combination, a shaft, a driven means,

a holding arm turning therewith, a driving means holding arm loosely mounted thereon, means for yieldingly connecting said arms to normally move together with said shaft until a predetermined resistance to said connection permits one of said arms to move relative to the other, and a manual means controlling and indicating the position of said yielding indicating means.

33. In combination, a shaft, a driven means, a holding arm turning therewith, a driving means holding arm loosely mounted thereon, means for yieldingly connecting said arms to normally move together with said shaft until a predetermined resistance to said connection permits one of said arms to move relative to the other, a manual means controlling and indicating the position of said yielding indicating means, yieldingly actuated means for normally operating said arms as a unit and independent yielding means for actuating one of said arms independent of the other into holding position.

34. In a timing mechanism, a shaft, a trip cam thereon, an actuating ratchet, a timing ratchet, a common pawl for said ratchets, an actuating ratchet for the timing ratchet, a

trip for controlling planetary gearing, a shaft actuating ratchet, a timing ratchet loosely mounted thereon, an actuating ratchet for the timing ratchet connected thereto and loosely mounted on said shaft, a common pawl for the first two ratchets, an independent pawl for the last ratchet, a common carrier pivotally mounted on said shaft for said pawls, a pawl actuating arm mounted on said shaft, and means connected to said gear 70 for actuating said pawl actuating arm, and yielding means connected to said shaft for restoring it to its initial position.

39. In combination, a shaft, a trip cam and trip for controlling planetary gearing, a 75 shaft actuating ratchet, a timing ratchet loosely mounted thereon, an actuating ratchet for the timing ratchet connected thereto and loosely mounted on said shaft, a common pawl for the first two ratchets, an independent pawl for the last ratchet, a common carrier pivotally mounted on said shaft for said pawls, a pawl actuating arm mounted on said shaft, means connected to said gearing for actuating said pawl actuating arm, timing yielding 80 means connected to said shaft for restoring it to its initial position, and a

- shaft, means connected to said gearing for actuating said pawl actuating arm, timing yielding means connected to said shaft for restoring it to its set position, and means for setting said yielding means in "off" position to bring the shaft actuating ratchet with its blank portion under its actuating pawl to render the planetary gearing inoperative or to hold said yielding means for intermittent operating condition, the extent of which depends upon the tension on said yielding means or to set the gearing for continuous operation by placing the yielding means in "bank" position by relieving the tension thereon entirely.
- 15 42. In combination, driving means, a driven shaft, planetary gearing interposed between it and the driving means, means for rendering said driven means intermittently operative, timing means including a pawl and ratchet therefor having means for rendering the driven shaft completely inoperative at predetermined intervals for a predetermined number of revolutions or continuously operative depending upon the setting of said timing means.

In testimony whereof, I affix my signature.
HARRY M. SWINDLER.
